UNITED STATES PATENT OFFICE.

FRANCIS DUFFY, OF CHICAGO, ILLINOIS.

FURNACE FOR STEAM-BOILERS.

977,078.

Specification of Letters Patent. Patented Nov. 29, 1910.

Application filed March 2, 1910. Serial No. 546,818.

To all whom it may concern:

Be it known that I, FRANCIS DUFFY, a citizen of the United States, residing at Chicago, in the county of Cook and State of Illinois, have invented a certain new and useful Improvement in Furnaces for Steam-Boilers, of which the following is a specification.

My invention relates to furnaces for steam boilers especially locomotive boilers and the object of the invention is to provide simple and efficient means for pre-heating and oxidizing the air entering into the fire box.

I accomplish my objects by employing a construction the preferred form of which is shown in the accompanying drawings, in which:

Figure 1 is a front elevation of a boiler furnace embodying my invention, Fig. 2 is a longitudinal sectional elevation taken on the line 2—2, Fig. 1, and Fig. 3 is a detail, drawn to an increased scale showing the most important parts of my invention. The plane of section of Fig. 3 is the same as that of Fig. 2.

Similar letters refer to similar parts throughout the several views.

Referring to the accompanying drawings, the fire box *a* is provided with grate bars *b*, and communicates with fire tubes *c*. Between the front wall *a'* of the fire box and the front wall *d'* of the boiler *d* is a space *e* which contains water. As the water in this space is adjacent to the fire box it will remain at a temperature approximately the same as the temperature of the water in the other parts of the boiler. There is an opening *e'* in the front of the boiler passing through the walls *a'* and *d'* for the introduction of coal and air into the fire box.

Secured to the front of the boiler surrounding the opening *e'* is a pre-heating chamber having a front wall *f* and peripheral walls *f'*. Said chamber has a door frame formed of walls *f''* arranged to register with the opening *e'* in the boiler front, these walls in the preferred construction being of cast metal integral with the portions *f* and *f'*. The frame is provided with a door *g* of ordinary construction.

The peripheral walls, *f'* of chamber *f* are apertured to admit of air being drawn into said chamber from all parts of the periphery thereof. Apertures *f''* are formed

in the walls *f''* and permit the air to pass from the chamber *f* into the door frame. By preference there is also a space *h* at the rim of the door frame which permits the air to pass directly from the chamber *f* into the opening *e'*.

At the inner margin of the door frame is formed a duct or passage *i* from which a number of small openings *i'* lead inwardly to the fire box through the opening *e'*. Said duct is for the purpose of introducing steam which is furnished through a supply pipe *j* shown in Fig. 1.

In operation the draft through the fire box causes air to be drawn into the chamber *f* through the apertures in the peripheral walls thereof, this air being finally drawn into the fire box through the apertures *f''* and opening *e'*. As the water in the space *e* keeps the boiler front *d'* at a high temperature, the air thus passing through the chamber *f* is heated by contact with said boiler front and therefore enters into the opening *e'* at a high temperature thus furnishing oxygen to the gases in the fire box in a heated condition. As a result the combustion is rapid and complete and the production of smoke is prevented. The chamber *f* thus constitutes a pre-heating chamber which enables air to be introduced directly into the fire box without chilling the gases and producing smoke but on the contrary prevents the formation of smoke. The metal adjacent to the duct *i* will be kept at a high temperature as a result of exposure to the heat of the fire box and hence said metal will superheat the steam entering the opening *e'* through the apertures *i'*. This super-heated steam, meeting the preheated air in the opening *e'* will cause a thorough commingling of heated air and steam prior to entrance into the fire box, with the result that a liberal supply of oxygen will be introduced into the fire box in heated condition, thus efficiently promoting combustion.

I claim as my invention:—

1. In combination, a steam boiler having a substantially flat front through which there is an opening leading into the fire box, and a shallow dished preheating chamber secured to the boiler front surrounding said opening and communicating therewith and contacting the boiler front at its periphery, the boiler front forming the back of the

preheating chamber, and said preheating chamber having inlets for air at its edges whereby the draft will draw air through said chamber across the boiler front before 5 entering the fire box.

2. In combination, a steam boiler having a fire-box and an opening in the front leading thereinto, and a flat preheating chamber secured to the boiler front surrounding said 10 opening and communicating therewith, said preheating chamber having inlets for air at its edges and having a steam duct with apertures arranged around the margin of said opening for the purpose described.

3. In combination, a steam boiler having a fire-box and an opening in the front leading thereinto, a steam duct arranged around the margin of said opening and having apertures leading thereinto, and a flat preheat- 15

20 ing chamber secured to the front of the boiler, and discharging into the boiler adja-

cent to the steam duct, substantially as described.

4. In combination, a steam boiler, having a fire-box and an opening in the front lead- 25

ing thereinto, and a flat preheating chamber secured to the boiler front surrounding said opening and communicating therewith, said preheating chamber consisting of cast metal and having a duct formed in the metal and 30 arranged to extend around the margin of said opening where it will be exposed to the heat of the fire in the fire box, there being small steam outlets leading from said duct into said opening, substantially as described. 35

In witness whereof, I have hereunto sub-
scribed my name in the presence of two wit-
nesses.

FRANCIS DUFFY.
